UNITED STATES PATENT OFFICE

SIMON P. JACKSON, OF KINSTON, NORTH CAROLINA

TOBACCO CUTTER

Application filed August 15, 1929. Serial No. 386,065.

This invention relates to improvements in tobacco cutters.

The invention more particularly relates to an attachment for a plug tobacco cutter, and has for its object to provide an attachment which may be secured to the conventional form of plug tobacco cutter and serve for accurately cutting pieces or sections from a plug of a predetermined size.

10 A further object of the invention is that the attachment serves for ejecting the piece or section cut from a plug of tobacco to a position within convenient reach of the operator.

15 It is also within the objects of the invention that the attachment be simple in construction and inexpensive to manufacture.

The invention is illustrated by way of example in the accompanying drawings, in 20 which:

Figure 1 is a perspective view of a conventional form of plug tobacco cutter with my attachment applied,

Figure 2 is a horizontal sectional view 25 taken substantially on the line 2—2 of Figure 3,

Figure 3 is a vertical sectional view taken substantially on the line 3—3 of Figure 2,

Figure 4 is a sectional view taken on the 30 line 4—4 of Figure 2,

Figure 5 is a fragmentary sectional view similar to Figure 2 and illustrating the ejector member and stops therefor,

Figure 6 is a perspective view of one of 35 the ejector stops, and

Figure 7 is a detail view showing the actuating bar employed for the stop shown in Figure 6.

Referring to the drawings in detail, the 40 conventional form of tobacco cutter to which my attachment may be applied may comprise a base 10 upon which is mounted a U-shaped frame 11. The frame 11 is provided with a suitable opening 12 in which there 45 is provided the one end of a handle or lever 13, said lever being connected to a blade 15 to impart upward and downward motion thereto for cutting plug tobacco in a manner well understood.

50 The cutter attachment constituting this

invention comprises a U-shaped frame 16, each leg of which terminates in a yoke 17 adapted to fit about the legs of the U-shaped cutter frame 11. The yokes 17 may be removably clamped to the frame 11 by screws or the like as shown at 18, Fig. 5. Within the frame 16 there is slidably fitted a cross-head 19. The member 19 carries a pin or rod 20 which is slidable within a tube 21 carried by the frame 16. A coil spring 22 is arranged by the frame 16. A coil spring 22 is arranged for pressing the bar 19 toward the cutter-blade 15.

Upon one leg of the U-shaped frame 16 there is secured a bar 23. The bar 23 is provided with two longitudinal slots 24 and 25. The slot 24 is adapted to accommodate the shank 26 of the stop-pin 27. Adjacent the free end of the shank 26 there is provided an elongated opening 28 adapted for loosely accommodating a pin 29 carried by the bar 23. The pin 27 extends through an opening in the associated leg of the U-shaped frame 16 and provides a stop for the cross-head 19 as best shown in Figure 5. Upon the bar 23 there is slidably a keeper-bar 30. The bar 30 is provided with slots 31, each slot being adapted for loosely receiving a screw 32. The screws 32 permit longitudinal movement of the bar 31. The one end of the bar 31, when positioned in Fig. 5, serves to keep the stop pin 27 in position for limiting the inward movement of the cross-head 19. A coil spring 33 tends to maintain the pin 27 in non-engaging position with the cross-bar 19.

Bar 31 carries a laterally extending arm 34 which has its outer end pivoted to a draw-bar 35. The draw-bar 35 is provided with a handle 36, a pointer 37, and a slot 38. A screw 39 holds the bar 35 in the position shown, and permits free longitudinal movement thereof. Also, it will be noted in Fig. 1, that the pointer 37 may be brought to register with either the number 10 or the number 5. These numbers are by preference placed upon the associated yoke 17, and form a purpose which will later appear.

In the slot 25 of the bar 30 there is pivoted a second stop 39 which is in the form of a bell-crank lever pivoted, as at 40. A suitable 100

spring 41^a urges the stop 39 to the position shown in Figure 5.

The frame 16 is provided with cover plates 41 which may be held in position by suitable bars and bolts as best shown in Figures 1 and 5, and thereby provide a pocket or receptacle 42 adapted for receiving a plug of tobacco.

In the use of my attachment, if it is desired to cut a portion from a plug of tobacco representing five cents worth, then the bar 35 is moved to bring its pointer in register with the number "5". This movement of the bar 35 shifts the bar 30 to the position shown in Fig. 5 and thus swings the pin 27 to provide a stop for the cross-head 19. A plug of tobacco can now be inserted beneath the blade 15 and into the pocket 42 to a point where the same engages the cross-head 19. The stop 39 swings upon its pin 40 to allow the insertion of the plug of tobacco. If the cutter is now operated to sever the plug of tobacco, and then lifted, there will be ejected from the pocket 42, a piece of plug tobacco equal in length to the distance between the blade 15 and cross-head 19. During ejection of the severed plug the stop 39 moves to the position shown in Figure 5 and limits outward movement of the cross-head 19. This movement of the stop 39 aids the cross-head 19, under the force of spring 22, in ejecting the piece of severed plug tobacco.

The piece of plug tobacco severed by the foregoing operation may represent five cents worth, and if it is desired to sever twice this amount or ten cents worth, then the bar 35 is operated to bring its pointer 37 in register with the number "10", Fig. 1. This movement of the bar 35 shifts the bar 30 to a position permitting the pin 27 to recede from the path of the cross-head 19, and a plug of tobacco may be inserted in pocket 42 to a greater degree, viz., the cross-bar 19 may be depressed until it engages the tube 21 and thus enable twice the amount of a plug to be severed than was the case with the pointer 37 of bar 35 registering with the number "5". The operation for cutting the larger piece of tobacco from a plug would, of course, be the same as that previously described for the smaller piece. Also, the larger piece would be ejected from the pocket 42 in the same manner.

I claim:

1. An attachment for a plug tobacco cutter comprising a receptacle and having a cutter blade, means for securing the receptacle to extend laterally from the cutter and in register with the cutter blade, means for limiting to different degrees the insertion of a plug of tobacco into said receptacle, and means for ejecting a severed section of a plug of tobacco from the receptacle upon raising the cutter blade.

2. An attachment for a plug tobacco cutter comprising a receptacle, means for de-

tachably securing the receptacle to extend laterally from the cutter and in register with the cutter blade, and means within the receptacle for limiting to different degrees the insertion of a plug of tobacco into said receptacle. 70

3. An attachment for a plug tobacco cutter comprising a receptacle, means for detachably securing the receptacle to extend laterally from the cutter and in register with the cutter blade, means within the receptacle and operable from the exterior thereof, for limiting to different degrees the insertion of a plug of tobacco into said receptacle. 75

4. An attachment for a plug tobacco cutter comprising a receptacle, means for detachably securing the receptacle to extend laterally from the cutter and in register with the cutter blade, a spring pressed cross-head within the receptacle, and means for limiting the inward and outward movement of said cross-head. 80

5. An attachment for a plug tobacco cutter comprising a receptacle, means for detachably securing the receptacle to extend laterally from the cutter and in register with the cutter blade, a spring pressed cross-head within the receptacle, means for limiting the inward and outward movement of said cross-head, and means operable at will from the exterior of the receptacle for further limiting the inward movement of the cross-head. 85 90

6. An attachment for a plug tobacco cutter comprising a receptacle, means for detachably securing the receptacle to extend laterally from the cutter and in register with the cutter blade, a spring pressed cross-head within the receptacle, means for limiting the inward and outward movement of said cross-head, a stop pin between the outward and inward limiting means for the movement of said cross-head, and means operable at will for bringing the stop pin into a position for further limiting the inward movement of the cross-head. 100 105 110

7. In a device of the character described, a receptacle adapted for receiving a plug of tobacco, a spring-pressed cross-head within the receptacle having limited outward and inward movement, a slidable bar carried by the receptacle, and a stop pin adapted to be actuated by the bar for further limiting the inward movement of said cross-head. 115

8. In a device of the character described, a receptacle adapted for receiving a plug of tobacco, a spring-pressed cross-head movable within the receptacle, means for limiting inward movement of the cross-head, and a spring-pressed stop adapted for limiting outward movement of the cross-head, and also adapted for assisting the cross-head in ejecting a piece of plug tobacco from said receptacle upon raising the cutter blade. 120 125
